DESIGN FOR A VELOCIPED

Wilbur Henry Adams, Cleveland, Ohio, assignor to The Colson Corporation, Elyria, Ohio, a corporation of Ohio

Application April 13, 1937, Serial No. 68,739

Term of patent 3½ years

To all whom it may concern:

Be it known that I, Wilbur Henry Adams, a citizen of the United States, residing at Cleveland, in the county of Cuyahoga and State of Ohio, have invented a new, original, and ornamental Design for a Velocipede, of which the following is a specification, reference being had to the accompanying drawing, forming part thereof, in which:

embodying my new design; and Figure 2 is a side elevation on a reduced scale of the velocipede shown in Figure 1.

The frame member shown in full lines in the drawing is the dominant feature of my design.

I claim:

The ornamental design for a velocipede substantially as shown and described.

WILBUR HENRY ADAMS.
